UNITED STATES PATENT OFFICE.

JOSEPH W. DEARING, OF LOS ANGELES, CALIFORNIA, ASSIGNOR OF ONE-HALF TO W. S. BULLIS, OF LOS ANGELES, CALIFORNIA.

AUTOMATIC BURNER-CONTROLLER.

No. 914,023.

Specification of Letters Patent. Patented March 2, 1909.

Application filed May 22, 1908. Serial No. 434,414.

To all whom it may concern:

Be it known that I, JOSEPH W. DEARING, a citizen of the United States, residing at Los Angeles, in the county of Los Angeles and 5 State of California, have invented a new and useful Automatic Burner-Controller, of which the following is a specification.

This invention relates to automatic cut-offs for burners and the main object of the 10 invention is to provide a device of the character described, which may be used with burners which burn gasoline or other fuel, which will automatically shut off the flow of fuel to the burner should the burner become 15 extinguished.

One of the primary objects of the invention is to shut off the flow of liquid so quickly after the flame has been extinguished that 20 none of the liquid fuel will escape. The device embraces a thermostatically controlled spring operated mechanism for shutting the valve automatically the spring operated mechanism being held in check when the thermostat is hot and being released and 25 allowed to close the valve upon the cooling and contraction of the thermostat.

Another object is to enable the valve to be 30 manually connected to regulate the flame without disturbing the spring actuated closing mechanism, the latter always being ready to shut the valve if the flame goes out, irrespective of the exact open position of the valve.

Another object of the invention is to compel 35 the operator to hold the valve open while the starting pan is being filled as otherwise it will automatically close so that no fuel will overflow from the starting pan and fill the stove, which heretofore has been the cause of 40 many serious explosions, as the operator would frequently open the valve to fill the starting pan and would then for some reason be called away from the stove and forget to return and shut the valve before the gasoline 45 overflowed and flooded the stove, and upon igniting the fuel in the starting pan the fuel which had escaped would take fire and explode.

In burners of the instantaneous type 50 equipped with my invention, the valve is opened wider than its normal burning position to permit gasoline to flow to the burner where it is ignited by the operator, and after burning the liquid gasoline a short time to 55 heat the generator, the valve is partially

closed to restrict the flow of gasoline and permit only enough to be fed to the burner to supply the necessary gas for the flame. And a further object of my invention is to provide means for automatically effecting 60 this partial closure of the valve when the generator has been sufficiently heated, this being effectuated by the spring operating device which commences to close the valve as soon as the valve has been opened, the thermostat being yet cold, a retarding device being employed to retard the closing movement of the valve so that it will remain wide open during the time requisite for the heating of the generator, and when the generator has 70 been heated sufficiently and the thermostatic device is in locking position, the valve will have moved to the regular burning position, whereupon the valve remains open so long as the flame is alive and keeps the generator 75 and thermostat hot, but upon the flame dying out or being extinguished the thermostat cools and unlocks the spring actuated mechanism which immediately closes the valve so that no gasoline can escape. 80

Referring to the drawings:—Figure 1 is a vertical cross section through a gasoline stove equipped with an ordinary type of burner in which a starting pan is employed, the burner being equipped with the invention. Fig. 2 is a vertical cross section through the burner and the automatic controlling device. Fig. 3 is a section on line x^3-x^3 Fig. 2. Fig. 4 is a section on line x^4-x^4 Fig. 2. Fig. 5 is an enlarged section 90 on line x^5-x^5 Fig. 1. Fig. 6 is a view similar to Fig. 1 showing the device applied to an instantaneous or flash burner, the retarding device being employed. Fig. 7 is an enlarged vertical section taken diametrically 95 through the retarding device and valve actuating mechanism. Fig. 8 is a section on line x^8-x^8 Fig. 7. Fig. 9 is a section on line x^9-x^9 Fig. 7.

Referring to Figs. 1 to 5 inclusive, 1 designates the stove with top plate 2. 3 is the retort or generator to which gasoline is supplied through an inlet pipe 4. The generator 3 has an extension 5 and two sleeves 6 and 7, which are in line with each other, 105 A vertical tube 8 extends through the extension 5 and is surmounted by a burner cap 9 the upper portion 10 of which is provided with radial orifices 11 and the lower drum 12 of which is provided with radial orifices 13. 110

The orifices 11 and 13 permit the passage of gas which forms the flame. A gas pipe 14 communicates with the generator 3 and as shown in Fig. 5 communicates with an off-set vertical pipe 15 having at its upper end a nozzle 16 which is controlled by a needle valve 17 on the other end of the rod 18 which is threaded in the lower end of pipe 15. A starting pan 19 is screwed to the lower end of the pipe 15. A horizontal valve rod 20 extends into the pipe 14 and carries a valve 21 adapted to open or close communication between pipe 14 and nozzle 16. A gasket 22 is arranged on the end of pipe 14 around the rod 20 to prevent leakage. Extending loosely through the sleeves 6 and 7 is a thermostat comprising a brass tube 23, one end of which is screwed to a stationary lug 24. Within the tube 23 is a steel rod 25, the rear end of which as shown in Fig. 2 abuts the end wall 26 of the tube 23, while its other end projects from the open end of the tube 23. 27 is a lock nut to secure the tube 23 in position. It is obvious that when the burner is in operation the tube 23 being of brass, will expand in length, slipping slightly in sleeves 6 and 7, which sleeves in addition to acting as guides for the tube form shields for the tube to protect the same so that the flames from the burner do not directly strike the tube and destroy it. If the flame becomes extinguished the tube will contact and push the rod 25 to the left. In order to accelerate the cooling action of the tube and its contained rod 25, the tube is provided with several perforations 28 which permit air to circulate inside the tube and around the rod 25. At the front end of the stove is a depending bracket 29 to which the lug 24 is secured. The bracket 29 is recessed and a lever 30 therein is pivoted at 31 below the rod 25, which rod contacts with lever 30 above the pivot 31 as shown in Fig. 2. The lower end of lever 30 engages a bell crank lever 32 also pivoted in the bracket 29, and the other arm of the bell crank lever 32 engages a lug 33 on a sliding bolt 34 which has an elongated eye 35 through which valve rod 20 passes and a spring 36 is arranged above the lug 33 to depress the bolt 34 when permitted by the tilting of the bell crank lever 32. The lower end of bolt 34 rides against and is supported by a roller 37. Revolubly mounted on rod 20 is a spring drum 38, the shell of which is provided with several notches 39 either of which is adapted to receive and be engaged by the bolt 34 when the latter is depressed. Within the spring drum 38 is a disk 40 attached by screws a to the bracket 29, and attached to disk 40 is the inner end of a spiral spring 41, the outer end of spring 41 being attached to a lug 42 on the spring drum 38. The spring drum 38 has an abutment 43 which is adapted to engage a pin 44 on the rod 20.

It is apparent that when the tube 23 is cold the spring 36 cannot depress bolt 34 because bell crank lever 32 cannot swing down being held by lever 30 which in turn is prevented from swinging its upper end to the right by reason of the rod 25 being held to the left by the contracted tube 23. At such times therefore the rod 20 and valve 21 are free to be turned counter-clockwise to open the valve as the spring drum 38 is not locked by bolt 34. When it is desired to start the stove the rod 20 is turned counter-clockwise to open valve 21 and as the rod 20 is thus turned it rotates the spring drum 38 with it through the medium of lugs 43 and 44, thereby placing the spring 41 under an increased tension tending to close the valve, and thus it is necessary for the person using the stove to hold the valve open to permit the gasoline to fill the starting pan as the spring drum is as yet unlocked, the thermostat being cold. The valve being thus held open gasoline flows through pipe 4, generator 3 and pipe 14 to pipe 15 and is projected upwardly by nozzle 16 and falls down into the starting pan. As soon as the starting pan is filled the valve 20 should be closed, either by the operator turning it clockwise, or by releasing it to allow it to close automatically under the spring tension. Then the gasoline in the starting pan is ignited and the flame therefrom heats the generator in a few moments so that the burner is ready for use. During this heating of the generator it is obvious that the tube 23 will also become heated and will expand, and the parts are so proportioned that by the time the generator 3 has become sufficiently hot the tube 23 will have expanded and permitted rod 25 to be moved to the right which movement of rod 25 is accomplished by the expansion of spring 36 operating bolt 34 downward to lock spring drum 38, and as bolt 34 is moved downward it operates lever 32 which in turn operates lever 30 and the latter then pushes rod 25 to the right. The spring drum 38 being now locked by the bolt 34, and the generator 3 being hot, the burner is ready for use, and upon opening valve 21 gas from the generator 3 is permitted to flow through pipe 14 to pipe 15 and out through nozzle 16 where it passes up through tube 8 and discharges laterally through orifices 11 and 13 where the flame is ignited. During this opening movement of valve 21 as the rod 20 turns its pin 44 strikes abutment 43 and turns the spring drum 38, thus winding up spring 41 as the disk 40 to which it is attached is stationary and as the spring drum thus turns it clicks over the end of bolt 34, the latter being beveled to permit of this action. One wall of each notch 39 is also beveled to permit of this opening movement. When the valve 21 has been opened the desired degree it is obvious that the abutment 43 will stand in contact with pin 44 and that the rod 20 may be turned clockwise to 130

reduce the flame without disturbing the spring drum, but that if the flame is to be increased the rod 20 must be turned counter-clockwise which will turn spring drum 38 further and increase the tension of spring 41. It is thus possible to adjust the flame to any point desired. The valve 18 is merely an independent valve which may be used for regulating the flame if desired, but has no essential bearing on this invention. Assuming now, for example, that the flame be blown out, the tube 23 will at once commence to cool, and as it cools it will contract in length and push rod 25 gradually to the left. During this cooling of the thermostat, the generator being still hot, will continue to form gas, which gas will escape from the nozzle 16, but the thermostat very quickly cools and pushes rod 25 to a point where through the medium of levers 30 and 32 it lifts the bolt 34 from its notch 39 and releases spring drum 38, whereupon spring 41 turns the spring drum clockwise and its abutment 43 acting on pin 44 rotates rod 20 and instantly closes valve 21 thus preventing further escape of gas. The cooling of the thermostat and closing action of the valve takes place while gas is still escaping. In other words, the valve is closed before the generator becomes so cool that the gasoline is not formed into gas and thus no gasoline in liquid form escapes from the nozzle. If the operator closes or partially closes the valve, the automatic device immediately operates upon the cooling of the thermostat. In this manner the valve is automatically closed and accidents are prevented. The burner may be re-lighted again in the manner previously described.

Figs. 6 to 9 inclusive show a modified form in which a retarding device is employed which is advantageous when the device is used with instantaneous or flash burners, or automatic water heaters. In this form of burner the construction is very similar except that the gasoline instead of first being lighted in the starting pan is lighted at the burner and the valve must be held open wider than its normal position in order to permit gasoline to escape in sufficient quantities to burn in liquid form. The retarding device is arranged to retard the closing movement of the valve while the thermostat is cool so that by the time the thermostat has become heated and locked the spring drum, the valve will have become closed to the burning point or point at which it permits the escape of gas for the burner in the desired quantity. In this form the bracket 29^a is longer and permits of using a single lever 30^a which is pivoted at 50 below its point of contact with rod 25. As shown in Fig. 7, the lower end of lever 30 engages a flange 51 on a stem 52 which is slidable in a wall 53 of the bracket 29^a and stem 52 also has a flange 54 with a spring 55 between the wall 53 and flange 54,

which has a tendency to force stem 52 to the left and tilt the upper end of lever 30^a to the right, which tilting movement is restricted by rod 25. The spring drum 38^a has notches 39^a which are adapted to be engaged by bolt 52. Within the drum 38^a is the spiral spring 41^a the outer end of which engages the drum and the inner end of which engages the stationery disk 40^a. Rod 20^a has a pin 43^a which co-acts with abutment 24^a on drum 75 38^a.

The retarding device consists of an internal gear 56 formed in the drum 38^a as clearly shown in Fig. 9, which meshes with a pinion 57 mounted to rotate on a stud 58 which projects from disk 40^a. Pivoted to a stud 59 is an escapement comprising a flat disk shaped weight 60 which encircles the hub of disk 40^a and which is adapted to swing relatively thereto by reason of its large hole, there being parallel pallets 61 above pivot 59 which co-act with pinion 57 to limit the rotation thereof to a speed permitted by the pendulum movement of the weight 60. The operation of this is similar to that previously described with the exception that the valve does not have to be held open as the operator has only to open the valve far enough to let the gasoline escape in liquid form, then ignite the gasoline whereupon the spring 41^a will commence to close the valve which closing action will be slow by reason of the described escapement, and by the time the valve has been sufficiently closed the thermostat will have become heated to permit spring 55 to expand and throw bolt 52 into engagement with the spring drum thus locking the spring drum against further rotative action on the valve, the valve then being in a proper position for the escape of gas at the burner.

What I claim is:

1. In combination with a burner and its valve, valve closing mechanism adapted when released to close the valve, a thermostat, means operated by the thermostat in heating to check, and in cooling, to release the valve closing mechanisms, said valve being movable independently of said valve closing mechanism permitting adjustment of the valve without disturbing the valve closing mechanism.

2. A thermostat comprising an expansible tube fixed at one end, and a rod having a less ratio of expansion arranged in said tube, one end of said rod being operated by the free end of said tube, a burner through which said tube extends, and sleeves on the burner surrounding the tube to shield it from the flame.

3. In combination, with an oil burner and its valve, spring operated mechanism for closing said valve, a thermostat controlled by the burner and mechanism operated by said thermostat for normally locking said

spring mechanism and permitting adjustment of the valve independently of the spring mechanism, while the flame is alive, and for unlocking the spring mechanism and 5 permitting it to close the valve when the thermostat cools upon the flame being extinguished.

4. In combination with a burner and its valve, spring operated mechanism for closing 10 said valve, a telescopic thermostat extending through the burner, a lever operated by the thermostat, means controlled by said lever for locking or unlocking said spring mechanism, and means permitting adjustment of 15 said valve when said spring mechanism is locked.

5. In combination with a burner and its valve, a spring drum revoluble on the valve stem, a stationary disk adjacent said drum, a 20 spring within the drum having one end attached to the drum, and its other end attached to the disk, means intermediate the drum and valve for rotating the latter upon rotation of the drum, and thermostatically controlled means for detachably locking the 25 spring drum from rotation.

6. In combination with a burner and its valve, a spring drum revoluble on the valve stem, a stationary disk adjacent said drum, a 30 spring within the drum having one end attached to the drum, and its other end attached to the disk, means intermediate the drum and valve stem for rotating the latter upon rotation of the drum, said spring drum 35 having notches, a spring pressed sliding bolt adapted to engage a notch of the spring drum, and thermostatically controlled means for withdrawing said bolt from engagement with the spring drum to permit the latter to rotate 40 the valve and close it.

7. In combination with a burner and its valve, a spring drum revoluble on the valve stem, a stationary disk adjacent said drum, a spring within the drum having one end attached 45 to the drum, and its other end attached to the disk, means intermediate the drum and valve stem for rotating the latter upon rotation of the drum, said spring drum having notches, a spring pressed sliding bolt 50 adapted to engage a notch and having a lug, a bell crank lever engaging said lug, a lever controlling the bell crank lever, and a thermostat passing through the burner for operating the second lever.

55. 8. In combination with a burner and its valve, a spring drum revoluble on the valve stem, a stationary disk adjacent said drum, a spring within the drum having one end attached 60 to the drum, and its other end attached to the disk, means intermediate the drum and valve stem for rotating the latter upon

rotation of the drum, said spring drum having notches, a spring pressed sliding bolt adapted to engage a notch and having a lug, a bell crank lever engaging said lug, a lever 65 controlling the bell crank lever, a telescope tube extending through the burner and fixed at one end adjacent the second lever, and a rod inside said tube with its end resting against the latter lever.

9. In combination with a burner and its valve, spring operated mechanism for closing said valve, said valve being capable of movement independently of the spring mechanism, a thermostat controlled by the burner 75 and mechanism operated by said thermostat for normally locking said spring mechanism while the flame is alive, and for unlocking the spring mechanism and permitting it to close the valve when the thermostat cools upon the flame being extinguished, and means for 80 retarding the closing movement of said valve.

10. In combination with a burner and its valve, spring operated mechanism for closing 85 said valve, a thermostat controlled by the burner and mechanism operated by said thermostat for normally locking said spring mechanism while the flame is alive, and for unlocking the spring mechanism and permitting it to close the valve when the thermostat 90 cools upon the flame being extinguished, means for retarding the closing movement of said valve, said retarding mechanism comprising an internal gear on the spring drum, a pinion meshing therewith, and an escape- 95 ment controlling said pinion.

11. In combination with a burner and its valve, spring operated mechanism for closing said valve, a thermostat controlled by the burner and mechanism operated by said 100 thermostat for normally locking said spring mechanism while the flame is alive, and for unlocking the spring mechanism and permitting it to close the valve when the thermostat cools upon the flame being extinguished, means for retarding the closing 105 movement of said valve, said retarding mechanism comprising an internal gear on the spring drum, a pinion meshing therewith, an escapement controlling said pinion, said escapement comprising a pivoted disk with a large perforation which receives the valve stem and permits it to swing relatively to said stem, and pallets on the pivoted disk 110 which engage said pinion.

In testimony whereof, I have hereunto set my hand at Los Angeles, California, this 15th day of May 1908.
